F. STRAUSS

PROCESS OF PRODUCING ORNAMENTAL SURFACES

Filed Jan. 11, 1922

Inventor
Ferdinand Strauss

By his Attorney,
Maurice Block

UNITED STATES PATENT OFFICE.

FERDINAND STRAUSS, OF NEW YORK, N. Y.

PROCESS OF PRODUCING ORNAMENTAL SURFACES.

Application filed January 11, 1922. Serial No. 528,392.

To all whom it may concern:

Be it known that I, FERDINAND STRAUSS, a resident of New York city, county and State of New York, and a citizen of the 5 United States of America, have invented certain new and useful Improvements in Processes of Producing Ornamental Surfaces, of which the following is a specification.

10 This invention relates to improvements in the art of producing ornamental surfaces or elements having ornamental surfaces, one of the objects being to provide an inexpensive but effective method by means of which surfaces, such as walls, ceilings, etc., can be decorated by unskilled hands or by which means ornamental wall paper and the like can be produced inexpensively. A further object of my invention is to provide an ornamental surface that will be in relief, that is to say, have the same appearance as an embossed surface. As a matter of fact, I am able to produce an ornamental surface having the same appearance as an embossed 25 surface, but at much less cost. By means of my improved method, I am able to decorate a wall quickly and at a small cost; or I may apply to a wall or ceiling paper the surface of which is treated in accordance with my 30 invention.

I will now proceed to describe my invention in detail, the novel features of which I will point out in the appended claims, reference being had to the accompanying drawing, wherein:—

Fig. 1 is a fragmentary view, illustrating the surface of a backing member decorated in accordance with my invention;

Fig. 2 is a sectional view thereof;

40 Fig. 3 is a fragmentary view illustrating a form of floral decoration; and

Fig. 4 is a similar view illustrating another embodiment of my invention.

To carry my invention into practice, I employ a backing member; said backing member may be a sheet of paper, cloth, leather or other pliable material, or it may be metal, wood or fibre. In other words, my invention is not restricted to any particular form of 45 backing member or any particular material to form a backing member. As one of the objects of my invention is to decorate the surface of a backing (whether solid or flexible), I merely treat the surface of any 50 material forming a backing member to be

decorated, such as a wall or partition, for instance. To carry out my invention, I prefer to first color the surface of the backing member with a selected aniline color, depending upon the final color or shade 60 which I desire to produce. After the backing element has been colored, I apply to same a film of transparent adhesive, to which I thereupon apply a layer of any element such as threads, flowers, hair or other 65 elements that will remain in relief or project from the adhesive after having been applied thereto. After the layer of projecting elements has been applied to the adhesive, I cover same with thin soft transparent 70 tissue paper to bind them in place so that they will not be rubbed off. The tissue paper may be colored paper or may be colored after having been applied. In Figs. 1, 2 and 3, the adhesive, which is applied to the 75 backing member 5, is indicated by stippling 6 and the projecting elements, which are applied to the adhesive, are indicated by 7 in Fig. 1. In Fig. 3 a floral sprig is indicated by 8. The layer of tissue paper which is 80 superimposed upon elements 7 and 8 is indicated by 9.

The elements 7 are promiscuously applied, that is to say, not in any regular order. The elements 7 may be composed of either 85 threads, hair, cord, grass, plant stems, or any similar elements, and will be scattered upon the film of adhesive substance. Should I desire floral decorations, I would apply sprigs 8 in some selected order. As the elements 7 or 8 will stand in relief or project from the surface of the backing, the layer of tissue paper will also stand in relief at the points where said paper bears upon the projecting elements. The tissue paper will 90 be pressed flat against the adhesive intermediate the projecting elements, as indicated in Fig. 2.

To obtain certain effects, an embossed leather effect for instance, I apply to the back 5 (see Fig. 4), a plurality of superimposed layers of tissue paper 10, 11 and 12, the layer 12 having applied thereto the adhesive 6 to which the elements 13 are applied. Over the elements 13 I apply a final 100 layer 14 of tissue paper. In this latter case, the backing will be colored, as in the form illustrated in Fig. 1, and each layer 10, 11 and 12 will be colored differently, all the 105 colors blending to produce a desired color 110

effect. The layers 10 and 11 will be flat, while layer 14 will have a roughened surface to conform with the disposition of the projecting elements 13.

5 In some instances, or to obtain certain desired results, I may utilize a colored adhesive instead of an adhesive which is colorless. To this colored adhesive I apply the projecting elements in manner described and then a 10 layer of tissue paper which I brush out to remove all wrinkles.

What I desire to secure by Letters Patent is:—

1. The method of decorating surfaces 15 which comprises first coloring the surface to be decorated; applying a film of transparent adhesive to the colored surface; applying a layer of projecting elements to the film of adhesive; applying a layer of thin 20 tissue paper over the projecting elements

and pressing it against the film of adhesive between the projecting elements; and finally coloring the layer of tissue paper.

2. The method of decorating surfaces 25 which comprises first coloring the surface to be decorated; applying a film of transparent adhesive to the colored surface; applying to said film of transparent adhesive a plurality of layers of thin tissue paper with transparent adhesive between each layer of paper; 30 applying a film of adhesive to the last layer of tissue paper; applying a layer of projecting elements to said last mentioned film of adhesive; and finally applying a thin 35 layer of tissue paper over said layer of projecting elements and pressing it against said last mentioned adhesive film between said projecting elements.

FERDINAND STRAUSS.
